Primary Examiner — Stacia A Cadmus*(74) Attorney, Agent, or Firm* — Reising Ethington P.C.; Jeffrey L. Doyle**CLAIM**

The ornamental design for a vehicle wheel front face, as shown and described.

DESCRIPTION

FIG. 1 is a front perspective view of the vehicle wheel front face;

FIG. 2 is a front elevation view thereof; and,

FIG. 3 is a side elevation view thereof.

In the drawings, the broken lines depict portions of the wheel front face that form no part of the claimed design.
